UNITED STATES PATENT OFFICE

EDMUND B. CARNES, OF NEW YORK, N. Y., ASSIGNOR TO CAIRNS DEVELOPMENT COMPANY, OF WILMINGTON, DELAWARE, A CORPORATION OF DELAWARE

METAL FUSELAGE

Application filed April 2, 1929. Serial No. 351,870.

My invention relates to improvements in metal fuselage construction for airplanes. More particularly this invention pertains to an improvement of the structure disclosed in application, Serial No. 173,086, filed May 5, 1927, for metal fuselage or body. In common with the best practice in this art the object of my invention is to produce a fuselage which can be economically made and assembled which will be as light as possibly consistent with the requisite strength, and which will offer the least air resistance. In attaining this object I employ three important factors:

- 15 A. The peculiar characteristics of these sheets;
  - B. The distribution of metal in the sheets which compose the fuselage; and
  - C. The shape of the fuselage.
- 20 A. One of the most important of factors in this invention is the characteristics of the metallic sheets from which the fuselage is formed. I shape these sheets in what I call compound curves for convenience of terminology, that is, curved sheets, which if sections are taken at any point would disclose arcs curving continuous inwardly.

The sheets are given a curvature along a transverse line by passing them between convex and concave rolls which are recessed. These rolls bear with a certain pressure upon the metal sheet. They may be either frictionally driven by the action of the sheet being pulled through them, or may be given a direct drive of the same or slower or circumferential speed as the speed at which the sheet is pulled through. The metal sheet itself may be pulled through the rollers by any conventional means. While the sheet is being pulled through the rollers another force is brought into play upon the sheet, and it is this force that imparts the compound curvature and tension to the sheet. This force is directed on to the sheet by causing a movement of the rolls in an upward or downward direction to the direction of pull upon the sheet. This movement when combined with the transverse curve being given to the sheet and the longitudinal pull thereon, distorts the sheet along its center line and in

gradually diminishing amounts towards each of its edges, with the result that the sheet is given a longitudinal curvature. The operation and movement of the rolls may be controlled in such a manner that the sheet 55 can be given a curve having radii which intersect at a point, or a curve having variable radii like the curve of a parabola. The sheet may also be given curves which blend from one form of curve into another. 60

As a result of having the sheet in compound curvature and as a result of the method of making in which the molecules of the metal are distorted in position, the entire fibre of the curved sheet is under tension. 65 The result is that the sheet because of this tension is extremely stiff, more rigid and quick in its reaction against the effect of a blow or pressure which might otherwise cause the sheet to become bent or distorted. 70 Due to these particular qualities the sheets are especially valuable in construction where a strong yet light structure is desired, for it can be seen that very little reinforcing is necessary inasmuch as the sheets after trimming are already formed to the shape desired. It is unnecessary to bend and fit them in shape to structural members or to hold them in place by the same. Further the curved sheets already have unusual 75 strength due to their inherent tension, their compound curvature, and the fact that they are preformed.

B. The metal sheets which I form into the compound curved sheets described above may 80 be formed of sheets of constant thickness, but I prefer to have the sheets of a tapering gauge, that is, to have the sheets tapered in thickness from the wider parts exposed to greater strain, towards the narrower parts 85 where there is less strain and so less metal required.

C. As to the shape of the structure, it is given a preferred stream-line outline. My 90 invention gives to the surface a smooth contour which offers very little resistance to the air. My fuselage may be built out of my compound curved sheets described above by trimming these sheets to the proper shape 95 and fitting them together. It is obvious that 100

on small structures it is possible to have one sheet forming an entire side. On the other hand, on large structures it is possible by properly forming the sheets to fit and fasten them together and still maintain the compound curvature over the whole surface.

A preferred structure would be a fuselage having in a general way three sides formed of compound curved sheets of the type described above. Such a structure is totally different from a triangular structure in which the sides are formed by placing a covering over a frame, for as described above, my compound curved sheets are already pre-formed. They are not bent into place over the braces which would give an arc of a polygon having a large radius as is the case in prior construction. On the contrary the compound curved sheets give continuous curves and have inherent in them a sufficient amount of strength, rigidity and stiffness to require very little bracing. Should a cross section be taken of a fuselage as described above, it would give a generally triangular figure. What it is, however, is a circular triangle and in which the radii of the arcs would intersect. It should be realized that such a cross section is inherent in the use of compound curved sheets.

Further objects and benefits of the invention will appear from the following description and accompanying drawings in which like reference characters denote like parts throughout the several views.

Figure 1 is a perspective view of a tapered sheet;

Figure 2 is a perspective view of a compound curved tapered side of a fuselage;

Figure 3 is a perspective and diagrammatic view of Figure 2;

Figure 4 is a perspective view of a fuselage;

Figure 5 is a perspective view showing a sectional side;

Figure 6 is a longitudinal cross section of my fuselage; and

Figure 7 is a modified form of my fuselage.

Referring more particularly to the drawings,

Figure 1 shows a sheet which is tapered in gauge in both directions from a middle portion.

Reference character 10 denotes the thicker section tapering at both ends to a narrow gauge as shown at 11. The tapering of the thickness of the metal has been exaggerated in order to make it more apparent.

Figure 2 is a perspective view of a side of a fuselage made from a sheet as shown at Figure 1 by imparting to it the compound curve and peculiar properties by a method such as has been described above.

After the sheet of Figure 1 has been drawn to the compound curve described above, it

may be trimmed to the desired shape giving the side sheet as shown in Figure 2.

Figure 3 is a perspective view of the sheets similar to Figure 2 with a diagrammatic representation which brings out the inherent curvatures of the sheet. The diagrammatic figures as designated by reference characters 12 are not intended to show ribs or bracing in a fuselage, but rather show the compound curvature of the sides of a fuselage and also show the circular triangular cross sections which are found in every section of the fuselage. It can be seen from this representation that such a triangular cross section is an inherent result in the formation of my fuselage when using three compound curved sheets. This result is totally different from that one obtained when the fuselage is built up by fitting sheets onto a frame work of circular triangular braces. It should be appreciated that not only are the circular triangular sections present at all points, but that the fuselage is continuously curved longitudinally, these curves merging with the circular triangle giving a member having locked stresses and thus great strength and rigidity.

The structural advantages in having circular triangular cross sections at all points in the fuselage are obvious. By my method a fuselage which is extremely rigid, strong, light and yet having a great resistance to sudden stresses, is obtained.

Figure 4 shows a perspective view of my fuselage. Any conventional method of fastening the side sheets together may be used. I have shown at 22 a preferred method in which I overlap the sides of the sheets. These then may be held together by riveting or welding.

In Figure 5 I have shown another method of forming my tapered side sheets in which the sections 16 and 17 may be worked on separately by the method described above imparting to them the compound curvature and other properties. They may then be fitted and fastened together giving a sheet similar to that shown in Figure 2. These sections 16 and 17 may be made from sheets which taper in thickness in one direction only and for this reason it may be that such sheets will be easier to work. The thickest part of the metal would be at 17^a tapering in gauge to the thin portion at 17^b. The sheets should be formed to arcs of the same compound curves so that when they are fitted together they will form continuous compound curves. This method is especially applicable when large fuselages are being constructed. It is, of course, possible to form the sheets and fit them together longitudinally in making a large side section as well as transversely as disclosed in Figure 5.

Figure 6 is a longitudinal cross section of my fuselage disclosing the tapering of the metal. At the point where the greatest

stresses are incurred the metal is the thickest as shown at 18, whereas at those points at which very little stress is brought to bear upon the fuselage, the metal has tapered to a thickness to give sufficient strength at that point as shown at 19.

In Figure 7 I have disclosed a modified form of my fuselage in which I have inserted a gusset 20 in the upper section. This modification or other similar modifications do not depart from my invention. Such a widening of the fuselage may be necessary in adapting the fuselage to certain types of motors or to a certain cabin arrangement and the like.

The method of making and the type of my structure I have shown in a generally simplified manner. To those who are skilled in the art it is obvious that there are many modifications. It is obvious, for example, that my structure is especially applicable to boat or pontoon construction, inasmuch as it has many characteristics in common with fuselage construction. Much less bracing would be needed and a lighter, stronger and more easily manufactured boat would result from using my type of structure. I therefore do not wish to be limited by my specification and drawings, but only by the prior art and the appended claims.

I claim:

1. A fuselage for aircraft, substantially triangular in cross section and made of three preformed sides tapering in wall thickness from a section of maximum stress to a section of minimum stress, each side having a convex curvature from one end to the other and having a continuous convex transverse curvature at all points along its length, whereby each side is longitudinally and transversely arched, such arched assembly of the three sides being substantially rigid in all dimensions.

2. An elongated metal body, adapted for use as a fuselage for aircraft, substantially triangular in cross section and made of three preformed sides tapering in wall thickness from a section of maximum stress to a section of minimum stress, each side having a convex curvature from one end to the other and having a continuous convex transverse curvature at all points along its length, whereby each side is longitudinally and transversely arched, such arched assembly of the three sides being substantially rigid in all dimensions, and means connecting the longitudinal marginal portions of the sides.

3. An elongated metal body, adapted for use as a fuselage for aircraft, substantially triangular in cross section and made of three preformed sides tapering in wall thickness from a section of maximum stress to a section of minimum stress, each side being preformed convexly at all points longitudinally and convexly at all points transversely of the fuselage whereby each side is longitudinally and

transversely arched, the sides being overlapped at the edges and secured together along the overlap, such overlapped portions forming longitudinally extending stiffening ribs.

In testimony whereof, I have signed my name to this specification this 28th day of March, 1929.

EDMUND B. CARNES.
